UNITED STATES PATENT OFFICE.

SAMUEL BEAUMONT JACKSON, OF QUINCY, MASSACHUSETTS.

FEEDING MECHANISM FOR METAL STRIPS.

1,283,522.

Specification of Letters Patent.

Patented Nov. 5, 1918.

Application filed October 21, 1914. Serial No. 867,878.

To all whom it may concern:

Be it known that I, SAMUEL BEAUMONT JACKSON, a citizen of the United States, and resident of Quincy, in the county of Norfolk and State of Massachusetts, have invented new and useful Improvements in Feeding Mechanism for Metal Strips, of which the following is a specification.

This invention relates to blank feeding mechanism for metal working machines, and while it is susceptible of use for other purposes, is particularly designed for feeding metal blanks, strips or plates to tack and nail making machines. The metal strips are of the required width for the length of the article to be made and are to be presented automatically to the cutting and shaping tools from a magazine containing a stack of such metal strips. The object of the invention is to provide simplified and dependable mechanism of novel and improved construction for automatically presenting blank strips, one by one, to the cutters and for performing all its functions of selecting and feeding the strips to the metal working machine automatically, so that no attention is required on the part of the operator other than to keep the magazine supplied with blanks or strips.

In the accompanying drawings which illustrate one embodiment of the invention, such embodiment constituting but one exemplification of the various forms in which the invention may be used,—

Figure 1 is a side elevation of an assembled blank feeding machine;

Fig. 2 is an enlarged sectional view on line 2—2 of Fig. 1, looking in the direction of the arrows;

Fig. 3 is an enlarged sectional view on line 3—3 of Fig. 1, looking in the direction of the arrows;

Fig. 4 is a plan view of the left hand end or forward end of the feed bar, showing the feed bar journal, the nipper, nose guide, stub end ejecting mechanism and strip locators;

Fig. 5 is a side elevation of the right hand end of the magazine and strip manipulating mechanism;

Fig. 6 is a vertical cross section through the feed bar and magazine showing one of the strip pushers and actuating mechanism therefor, a strip presser foot in operative position, and a strip guide in a raised or inoperative position;

Fig. 7 is an enlarged view in plan of the forward end or left hand end of a strip pusher;

Fig. 8 is a vertical cross section of the feed bar with a strip thereon, a strip guide 60 in operative position, a retracted strip pusher and a strip presser foot in operative position;

Fig. 9 is a vertical cross section of the feed bar showing a pair of strip keepers in 65 closed position over the strip;

Fig. 10 is an enlarged central vertical section of the right hand end of the feed bar, showing the feed bar starting and stopping mechanism and the spur and annular gears 70 for actuating the nipper driving shaft;

Fig. 11 is a side elevation of the left hand end or forward end of the feed bar showing the nose guide, stub end ejecting mechanism and a pair of strip keepers;

Fig. 12 is a side elevation of a portion of the feed bar near the right hand end showing the sliding bar which actuates the strip keepers;

Fig. 13 is a bottom plan view of a portion 80 of the feed bar and strip keeper opening and closing mechanism;

Fig. 14 is an end elevation of the left hand end of the clutch housing showing the bevel driving gear and the clutch controlling 85 mechanism;

Fig. 15 is a vertical sectional view on line 15—15 of Fig. 14, looking in the direction of the arrows;

Fig. 16 is a central vertical section through the nipper actuating clutch, showing the clutch shifter and the cam shaft clutch controlling worm;

Fig. 17 is a horizontal central section on the line 17—17 of Fig. 15;

Fig. 18 is a transverse section on the line 18—18 of Fig. 16, showing the clutch mechanism; and

Fig. 19 is a horizontal section on line 19—19 of Fig. 14, enlarged.

The frame of the machine consists of the clutch housing 4 at the left hand end as viewed in Fig. 1, the feed bar housing support 5 at the right hand end, and the magazine supporting rod 6, all rigidly keyed together. Said frame is supported at the left hand end by a lateral adjustment swivel 7 (Figs. 1 and 2) carried by a bracket 8, which is connected to the tack or nail machine M (Fig. 1); and at the right hand end by a 110

radial adjustment shoe 9 on a standard composed of parts 10, 11 and 12 resting on the floor.

The magazine for holding the strips or blanks consists of the clutch housing 4 mounted on lateral adjustment swivel 7, brackets 13 and 14 supported on rod 6; the uprights 15, 16, (Figs. 1 and 2) mounted on clutch housing 4 and 17, 18 and 19 (Fig. 1) mounted respectively on brackets 13 and 14, forming combined vertical and inclined guide channels for receiving the strips or blanks S (Fig. 2) and holding the strips in a stack in position to be delivered one by one from the bottom of the stack by the feed mechanism hereinafter described.

In place of the feed tube or barrel which is commonly employed as the guiding and feeding means for the blanks on machines to which this invention is applicable, I use the feed bar 20, which possesses the advantage, among others, that it will not so readily accumulate dirt or lime dust, (a result of the pickling process for removing the scale from the steel, the lime dip being used as a rust preventative), as a tube or similar structure. Such accumulation might frequently render the machine inoperative.

Said feed bar 20 is rigidly attached at its right hand end within a sleeve 21 (Figs. 3 and 10) and rotates, with sleeve 21 as a bearing, in swivel journal 22 mounted in the feed bar housing 23 which is supported by the frame. At its left hand end the feed bar 20 is provided with a sleeve bearing 24 (Figs. 4 and 2) which turns in journal 25. The journal 25 is mounted to slide up and down on posts 26 carried on a bracket 27 and attached to clutch housing 4 of the frame. The bar 20 may be rotated a half revolution between the several cutting operations, for the purpose of obtaining the angular cuts which form the points when the tacks or nails are cut from the strips. The rotation of the feed bar 20, with the nose guide rigidly fixed thereto and resting on the lower cutting tool of the tack or nail machine, is permitted by the vertical sliding of the journal 25 on posts 26, which allows the feed bar to rise and fall a little as the nose guide turns over on the cutting tool. The journal 25, however, prevents any lateral vibration of the feed bar.

The nipper slide 29 which carries the strip or blank forward to the cutting tools, is slidably mounted on the feed bar 20 (Figs. 2 and 5) and travels between its forward position as shown in Fig. 1 and a rear position somewhat to the right of that shown in Fig. 5 near the right hand end of the machine. The nipper jaw 29^b is pivoted to the forward end of the slide 29 which forms the lower jaw of the nippers and is mounted within a dovetailed recess 20^c in feed bar 20. A spring 30 underneath the nipper jaw 29^b (Fig. 5) tends to close the nipper jaw; and

when all of the strip has been cut excepting the stub end 31 (Fig. 4) the nipper opening arm 32 mounted on shaft 33 (Figs. 1 and 2) forcibly opens the nipper so that the stub end 31 is not withdrawn by the nipper. Cam 71 153 (Figs. 1 and 5) operates the arm 32 acting through lever 154 and shaft 33. The nipper 29 is moved back and forth along the bar 20 by suitably disposed pinions 34^a—34^c (Figs. 4, 2 and 1) rotatably mounted on the feed bar. These pinions rotate synchronously so that the pinion 34^a at the extreme left, meshing with the rack 29^a (Fig. 4) withdraws the nipper to the right and until pinion 34^b meshes with the rack 29^a. The pinions 34^a, 34^b, 34^c, 34^d, 34^e, 34^f, coöperate with the rack 29^a to move the nipper from its forward position as shown in Figs. 1 and 4, to the position somewhat to the right of that shown in Fig. 5 near the right hand or rearward end of the machine; and are actuated by miter gears 35 driven by shaft 36 (Fig. 5) mounted on and beneath the feed bar 20. Shaft 36 is provided at its right hand extremity with a pinion 37 which is driven by an annular gear 38 (Figs. 3 and 10) rotatably mounted on sleeve 21 (Fig. 10); annular gear 38 having an external spur gear 38^a made integral therewith is driven by spur gear 39 on nipper actuating clutch shaft 40 rotatably mounted in clutch housing 4, brackets 13, 14 and feed bar housing 23.

Keyed to shaft 40 by keys 41 (Fig. 16) are cam plates 42 and 43 fitting loosely within annular recesses 44^a and 45^a in clutch gears 44 and 45. Each of said cam plates is made with two oppositely disposed cam-like recesses in which are mounted clutch rolls 46 and 47 (Fig. 18). Springs 48 and 49 tend to force said rolls up the cam surfaces into engagement with the periphery of the annular recess 44^a in gear 44, thereby coupling the gear 44 and the cam plate 42 together. Said rollers are disengaged from clutching position by clutch levers 50 and 51, pivoted on cam plate 42, and carrying studs 52 and 53 which engage the rollers 46 and 47 on the sides opposite to the springs. Each clutch lever 50 and 51 has at its inner end a clutch pin 54 and 55, which drops into an annular groove 57^a of the clutch shipper 57, when the latter is shifted endwise to bring the groove opposite said clutch pins. In this position the clutch will be engaged. When the shipper is shifted so as to force the pins 54 and 55 out of said groove, the levers 50 and 51 will be swung on their pivots and move the rolls 46 and 47 down the cam surfaces and uncouple the gear 44 from its cam plate. It will be understood that there are two identical clutching devices and that they are respectively coupled to gear 44 or to gear 45 according to the position of groove 57^a of the shipper so that the rotation of the shaft 1

40 may be reversed; gears 44 and 45 being rotated in opposite directions as shown by arrows in Fig. 16 by means hereinafter described. When the annular groove 57^a is in neutral position between the two sets of pins 54 and 55, both sets of rolls are released and the shaft 40 is uncoupled from both gears.

When the nipper withdraws toward the right or rear end of the machine leaving the 10 stub end 31 in the nose guide 28 and stub end ejectors 58 (Figs. 4 and 11), the stub end remains in such position until the nipper reaches a position somewhat to the right of that shown in Fig. 5 and is approaching the 15 end of its travel. Thereupon the nipper engages pin 59 (Fig. 12) mounted on shifting bar 60 at a point near the end of the travel of the nipper, and moves pin 59 to the right, shifting the bar 60 with it. As the shifting 20 bar 60, with stub end ejectors 58 mounted thereon, moves to the right the stub end is removed from the nose guide 28 and is dropped from between the ejectors 58 when the inwardly projecting arms 58^a engage 25 with the stop 61, and cause the ejectors 58 to spread apart. Said stub end ejectors 58 are 30 yielding urged inwardly by spring 62 (Fig. 4) and thereby exert a gripping tension on the edges of strips of various widths for the purpose of removing the stub end 35 from the cutting tools through the nose guide 28.

The feed bar 20 is provided with a series of strip keepers for holding the strip or 40 blank in position on the feed bar and to counteract any tendency in the strip to warp or curl. Said strip keepers as herein shown consist of arms 63 (Figs. 9, 11 and 13) rigidly secured to studs 64 which turn in the 45 feed bar 20. The strip keepers are opened and closed by strip keeper actuating mechanism comprising a strip keeper shifting bar 60, mounted so as to slide on the under side of feed bar 20 by means of screws 65 passing through slots in the bar 60, which limit the endwise movement of the bar 60. Arms or links 66 (Fig. 13) are rigidly secured to the several studs 64 and are pivotally connected to bar 60 by a slot and pin connection where- 50 by the endwise movement of bar 60 will cause the keepers 63 to swing inwardly or outwardly over the channel provided in the feed bar 20 for the strip or blank. When the right hand end of nipper 29 strikes pin 55 59 (Fig. 12) mounted on the bar 60, the shifting bar 60 is carried with the nipper to the extremity of its slots through which screws 65 pass, thereby operating links 66 and swinging the strip keepers to open position parallel with the feed bar 20, instead of 60 across the feed bar as shown by dotted lines in Fig. 13. As the nipper 29 moved forward to the left, spring 67 (Fig. 13) rigidly fixed on one end to screw 65 and on the other 65 end to shifting bar 60, serves to move the

shifting bar 60 toward the left in the direction to close the strip keepers as illustrated in Fig. 13. To obviate the necessity for a fine adjustment of the clutch which controls the forward and reverse movement of the 70 nipper, bar 60 is shown in two parts yielding joined together longitudinally by a spring 68 (Fig. 12) whose right and left ends are mounted on the two portions respectively of the bar 60.

Above the feed bar 20 and near each end of the strip magazine, is a presser foot 69 (Figs. 2, 5, 6 and 8) extending laterally from a presser foot slide 70 which works in a vertical guideway 71. The slide 70 is 80 moved up and down by a bell crank lever 72 pivoted on stud 73 which is secured to a bracket extending from guideway 71. The lower arm of bell crank lever 72 is connected by link 74 to the upper end of lever 75. 85 Lever 75 is pivotally mounted on bracket 76 by screw 77 and normally urges link 74 toward the right by a tension spring 78 (Fig. 5). Cam 79, mounted on cam shaft 80, engages roll 81 on lever 75 and controls the 90 upward and downward movement of the presser foot.

The strips or blanks are pushed out from the bottom of the stack in the magazine by strip pushers 82 (Figs. 6 and 5) of which 95 there are three slidably mounted in the clutch housing 4 and magazine brackets 13 and 14 (Fig. 1). The operative end of each pusher 82 is formed to engage the lowermost strip in the magazine (Figs. 2 and 6) 100 and force it out under presser feet 69, 69, to a position over the feed bar 20 (Fig. 6); each pusher 82 is provided with a downwardly yielding leaf spring 82^a mounted on the pusher and permits of the easy withdrawal of the pushers as they pass under the stack, said spring projecting above the surface of the pusher a sufficient amount to engage the bottom strip. The three strip pushers 82 are actuated by the cam 83 rigidly mounted on cam shaft 80 (Fig. 6) 105 through the following mechanism:—Arms 84 rigidly mounted on rock shaft 85, engage pins 86 in the pushers 82 and the roll 87 mounted on the downwardly extending arm 110 on the middle arm 84, by means of the tension spring 88, is held in contact with the cam surface of cam 83 thereby imparting a reciprocating motion to the pushers as the cam shaft 80 rotates.

Strip guides 89, 89, adjustable for different widths of strips are carried on laterally extending arms or slides 90, (Figs. 2, 6 and 8) which work in vertical slideways 91. Each slide 90 is actuated by a bell crank lever 92 115 fulcrumed on stud 73. The lower arm of lever 92 is connected by link 93 to the upper end of lever 94, which is pivotally mounted on bracket 76 by screw 77 and normally urges link 93 to the right by a tension spring 120 130

similar to 78 (not shown) but located in front of spring 78 (Fig. 5). Cam 79 mounted on cam shaft 80 engages roll 96 on lever 94 and controls the upward and downward movement of the strip guides. When the guides are down on the feed bar, clamping plungers 97, three in number, (Figs. 2 and 5) are brought down on the strip 98 to the position shown in Fig. 5. The mechanism for effecting this consists of a plunger guide rail 99, which is bolted to slides 90 and provided with holes through which plungers 97 extend. Plungers 97 are held in raised position on rail 99 by coil springs 100. Plunger levers 101, one for each plunger, are pivoted to guide rail 99; one arm of each lever 101 acts on the plunger 97, and the other arm is pivoted to link 102; in the right hand end of link 102 is mounted pin 103. A lever 104 fulcrumed on screw 77 (Fig. 5) engages at its upper end pin 103 and by means of cam 79 actuating roll 105 on lever 104 operates the clamping plungers. Said strip is held thus clamped until the strip keepers 63 close over the strip 98 as shown in Fig. 9, and the strip is engaged by the nipper. After the strip keepers close over the strip and the strip is engaged by the nipper the three cam paths on cam 79 operate to raise the strip presser feet, strip guides and clamping plungers to their respective elevated positions as shown in Figs. 1 and 2.

The feed bar rotating mechanism for turning the strip over between each action of the cutting tools, is quite different from the oscillating method commonly used, in that the feed bar is rotated half a revolution and stops while the tack or nail blank is severed from the strip, and turns the succeeding half revolution in the same direction as the preceding one; thus giving the feed bar intermittent rotation in one direction; the mechanism comprises lever 106 (Fig. 1) pivoted on a bracket 107 rigidly mounted on a leg of the tack or nail machine, reciprocating rods 108 and 109, extending from lever 106 lengthwise of the machine, ratchet arms 110 and 111, pawls 112 and 113 (Figs. 1 and 3) ratchet wheel 114 rigidly mounted on stud 115, journaled in feed bar housing 23, bevel gear 116 rigidly mounted on stud 115, bevel pinion 117 (Figs. 1, 3 and 10) rotatably mounted on sleeve 21 which carries the feed bar; sleeve 21 being rotatably mounted in feed bar housing 23. The lever 106 is reciprocated by suitable mechanism (not shown) on the tack machine and imparts sufficient motion to arms 110 and 111 to permit the engagement of pawls 112 and 113 with the ratchet teeth on the ratchet wheel 114. The pause in the rotation of the feed bar 20 while the blanks are severed from the strips, is effected by slightly increasing the stroke of arms 110 and 111 so

that pawls 112 and 113 will pass slightly beyond the point necessary to engage a tooth on the ratchet.

In order to stop the rotation of the feed bar 20 while the stub end of the strip is being removed and a fresh strip is seized by the nippers and presented to the cutting tools, and again to start the rotation of feed bar 20, the following stopping and starting mechanism is provided: 118 (Figs. 75 3 and 10) is a stopping and starting cam rigidly mounted on cam shaft 80. Cam shaft 80 is actuated by mechanism hereinafter described and rotates only while the stub end of the used up strip is being removed and a fresh strip is being brought into position to be operated upon. While this is taking place, therefore, feed bar 20 and sleeve 21 should be disconnected from gear 117 which drives the feed bar, and is loose on sleeve 21. 85 A rock shaft 122^a extending transversely through sleeve 21 and feed bar 20 has at one end a clutch finger 123 which normally engages a pin 124 on gear 117, thereby causing the feed bar to turn with the gear. 90 At the other end of rock shaft 122^a is an arm 122 having a roller 121 at its outer end. The cam lever 120, carrying cam roll 119, is fulcrumed on a bracket extending from the feed bar housing 23. Said lever 120 has 95 at its upper end a cam surface 120^a which is out of the path of roller 121 on arm 122 when the feed bar is rotating and the cam shaft 80 is inactive. When the cam shaft 80 is rotated, cam 118 acting through cam 100 roller 119 swings lever 120 so as to move its cam surface 120^a into the path of roller 121 on arm 122, thereby swinging arm 122 and disengaging clutch finger 123 from pin 124. Gear 117 and feed bar 20 are thus disconnected and the gear is free to rotate while the feed bar remains at rest in the proper position to receive a fresh strip. The cam 118 is so shaped as to hold the clutch finger 123 out of engagement with pin 124 110 so long as said operations of removing the old strip stub and seizing a fresh strip continue, and then to reengage said clutch finger and pin.

The clutch controlling mechanism (Figs. 115 14 and 15) comprises nipper clutch cam 125, rigidly mounted on cam shaft 80 and provided with forward reversing cam path 125^a, backward reversing cam path 125^b, and neutral cam path 125^c, shifting lever 126 120 fulcrumed at 126^a on the clutch housing, spool fork 127 engaging clutch shipper 57 to shift the clutch as the cam projections on cam 125 engage the roll 128 on the lever 126.

During the cutting of the strips, the strips 125 are fed forward toward the cutting tools by means of the feed bar rotating mechanism. As the feed bar 20, (Fig. 3) is rotated in a clockwise direction, with the nipper clutch Fig. 16 in neutral position, pinion 37 130

mounted on shaft 36 of the feed bar rotates on its axis in an anti clockwise direction and thereby rotates the pinions 34 (Figs. 1 and 5) which mesh with and drive the rack 29^a 5 and nipper 29, in a direction to feed the strip to the cutting tools; when the strip has been fed up to the gage 129 (Fig. 1) pinion 37 no longer rotates on its axis but continues its clockwise movement with the 10 feed bar, carrying with it the annular gear 38, spur gear 39, and shaft 40 drive clutch (Fig. 16) being disengaged until the half revolution of the feed bar is completed. At the end of the half revolution the tack or 15 nail blank is severed from the strip, and after the cutting tool is withdrawn, the strip is moved forward again to the gage 129 by the rotation which is resumed of gear 37, shaft 36 and the rack and pinions 20 which drive the nipper endwise.

The clutch mechanism for actuating the cam shaft 80, (Figs. 14 and 15) comprises worm 130, rigidly mounted on the left hand end of shaft 40, plunger 131 (Figs. 14 and 25 19) plunger spring 132, plunger trigger 133, trigger spring 134, all mounted on shifting lever 135 which is mounted on the frame, trigger stop screw 136, spool fork 137, shifting spool 138, clutch shipper 139 (Fig. 17), 30 pin 140 loosely mounted in the housing 4 of the frame, clutch shifting cam 141 on cam shaft 80. As the clutch proper 142^a for cam shaft 80 is identical, except that it requires no reverse movement, with the nipper 35 clutch shown and described under Fig. 16, it is not described in detail here.

When the seat 131^a of plunger 131 engages the worm thread on worm 130, the upper arm of shifting lever 135 moves toward the 40 left as shaft 40 rotates in a counter-clockwise direction; the lower arm of shifting lever 135 forces in shifting spool 138 and shipper 139 which is connected to it, until the cam clutch 142^a and gear 142 are locked together thereby rotating the cam shaft 80. Plunger 131 is disengaged from worm 130 by the forcing out of the plunger as the bottom of the plunger bears against the gradual rise 130^a in the bottom of the worm thread. 45 The bottom of the groove or thread at the left hand end of the worm acts as a cam during a half revolution of the worm, thereby forcing the plunger out. The plunger is then held out of engagement with the worm by the trigger 133, pressed into the annular groove 131^b in the plunger by the leaf spring 134. When the cam shaft 80 has made one revolution it is stopped by the movement of shipper 139 toward the left. 50 Cam 141 acting on pin 140 unlocks gear 142 and cam shaft 80 thereby stops. The left hand movement of the shipper 139 and shifting spool 138 carries the upper arm of shifting lever 135 and plunger 131 toward 55 the right until trigger 133 strikes against

trigger stop screw 136 and plunger 131 is released and forced into engagement with worm 130 by the compression spring 132.

The nipper clutch gears 44 and 45 are continuously driven in opposite directions 70 by a sleeve 143 loosely mounted on rock shaft 85 (Fig. 15) and driven by bevel pinion 144 on a shaft journaled in clutch housing 4 of the frame (Figs. 2 and 15); said shaft being continuously driven by a 75 pulley 146 (Fig. 2) which is rotated by a belt from a pulley on the tack machine (not shown). Sleeve 143 has integral therewith, bevel gear 145, (which meshes with and is continuously driven by bevel pinion 144), 80 pinion 147 which meshes with clutch gear 142 to drive the cam shaft 80, spur gear 148 which meshes directly with clutch gear 44 to drive the nipper in one direction, spur gear 149 which meshes with an intermediate 85 gear 150, which in turn meshes with clutch gear 45 to drive the nipper in the opposite direction, according as the clutch mechanism, heretofore described, locks cam plate 42 or 43 with gears 44 or 45. 90

The operation of the machine is as follows: Assuming that the nipper 29 is traveling to the left as viewed in Fig. 1, and that the strip has been all cut excepting the stub end (31 in Fig. 4) held by the nipper jaws, as the nipper approaches the nose guide 28, located close to the cutters, cam shaft 80 stopped during the cutting of the strip, is made to rotate by the throwing in of the cam shaft clutch actuated by the 100 worm 130 and plunger 131 (Fig. 15), and the reversing projection 125^b on cam 125 shifts the nipper clutch into backward reversing position. Thereupon, the nipper 29 will start its travel toward the right and 105 away from the cutting tools. Simultaneously with the shifting of the nipper clutch into backward reversing position, the nipper opening arm 32 on shaft 33 engages the upper jaw 29^b of the nipper and forces the 110 right hand end thereof down and opens the nipper so that as the nipper moves to the right the stub end remains in the nose guide 28 and in stub end ejectors 58 until the nipper reaches a position at the right hand end 115 of the machine. As the nipper in its travel toward the right engages pin 59 on bar 60 (Fig. 12), shifting bar 60 moving with the nipper, retracts the stub end held by the strip locators 151 (Fig. 4) mounted on the 120 tack or nail machine (not shown) and strip ejectors 58, until the inwardly projecting arms 58^a mounted on bar 60 (Fig. 4) strike the stop screw 61, thereby opening the ejectors 58 and discharging the stub end. 125 The rotation of the feed bar will also be stopped as cam 118 on cam shaft 80 actuates the clutch finger 123 by swinging the cam surface 120^a of lever 120 toward the right and into the path of roll 121 on arm 122, 130

mounted on and rotating with the feed bar. This disconnects the driving gears 116 and 117 from operative connection with the feed bar 20 and thereby stops the feed bar in 5 correct position to receive a fresh strip.

As the nipper travels to the right and engages pin 59 on bar 60, the strip keepers 63 are opened. After the nipper passes the right hand presser foot, cam path 79^a on 10 cam 79 (Fig. 5) actuates arm 75 and the strip presser feet 69, 69, drop into operative position. A fresh strip is next pushed from beneath the stack of strips in the magazine by the engagement of the cam 83, on 15 cam shaft 80, with the strip pusher arm 84 (Fig. 6) on rock shaft 85. This causes the shaft 85 to rock and to actuate the three strip pushers 82, which are located near the two ends and the middle of the strip, and 20 forces the strip out from the bottom of the stack over the feed bar 20 and beneath the presser feet 69, 69. Cam path 79^b on cam 79 next engages roll 96 and moves the upper arm of lever 94 toward the right, thereby 25 dropping strip guides 89 into operative position at the sides of the strip (Fig. 8). Cam 83 next actuates the strip pushers to withdraw them and the strip is allowed to drop from the strip pushers to the feed bar, 30 where it is clamped by the clamping plungers 97, actuated by levers 101, link 102, pin 103, and clamp actuator lever 104, which is operated through roller 105 by cam path 79^c on cam 79, immediately after the withdrawal of the strip pushers. While the strip 35 is thus firmly clamped to the feed bar and the cam projection 125^a on cam 125, shifts the nipper clutch into forward reverse position by connecting cam plate 43 and gear 45, so 40 that the nipper moves in a direction toward the cutting tools, shifting bars 60 moves to the left and the strip keepers 63 close over the strip. Arm 152 and lever 154 (Fig. 5) are rigidly keyed to the rock shaft 33. As the 45 right hand end of the upper jaw of nipper 29 passes under the nipper opening arm 152, cam 153 on cam shaft 80, actuating arm 154 (Figs. 1 and 5) swings arm 152 in a downward direction into the path of nipper jaw 50 29^b, thereby opening the nipper to receive a fresh strip and as the nipper moves toward the cutting tools engaging the fresh strip, and passes from under the arm 152, spring 30 (Fig. 5) closes the nipper and the strip 55 is firmly held by the nipper. Cam 79 next actuates arms 75, 94 and 104 and raises the strip presser feet 69 and strip guides 89 together with clamping plungers 97 clear of the feed bar. The nipper is now free to 60 pass under the strip presser feet, strip guides and clamping plungers.

Cam 118 next actuates the lever which permits clutch finger 123 to reengage the pin 124 and thereby connects the feed bar rotating mechanism and the feed bar resumes its

intermittent rotation. At this juncture, cam projection 125^c on cam 125, engages lever 126 and shifts the nipper clutch from its forward operating position, into neutral position, so that the clutch plates 42, 43 (Fig. 16) are disconnected from both clutch gears. Thereupon, the nipper and strip will be fed toward the cutting tools by the action of the feed bar rotating mechanism and annular gear rotatably mounted on the feed bar. 75 As the nipper clutch is shifting into neutral position, cam 141 acting on pin 140 (Figs. 17 and 15) forces shifting spool 138 to the left and thereby disconnects clutch gear 142 from shaft 80 and said shaft 80 stops. The upper arm of shifting lever 135 with plunger 131 mounted therein, by the operation of cam 141 is brought into a position where trigger 133 striking against trigger stop screw 136 releases the plunger and the cycle 80 of operations is complete. 85

From the foregoing description of the construction and mode of operation of the machine, it will be seen that the strip keepers will hold the blank or strip substantially flat on the feed bar and afford substantially continuous support for the strip on both its upper and lower sides, thus preventing the strip from bending, buckling or warping during the intermittent rotation of the feed 90 bar and while being fed forward by the nipper along the feed bar, which also acts as nipper guiding means; that the nose guide 28 and strip locators 151 constitute 95 guiding means for the strip at its forward end, adapted respectively to prevent vertical and edgewise displacement of the strip during the operation of the feed bar; that the stub end ejectors 58 will hold the stub end of the strip in the guide until after the nipper 100 has released the strip and withdrawn, and will then retract the strip from the strip guiding means and open to drop out the stub end; that the magazine for holding the stack of strips S, is substantially vertical at its 105 lower part immediately above its delivery end and inclined at its upper part, whereby the inclined part of the magazine will take a great part of the weight off from the lower strips in the stack while the vertical part 110 at the lower end of the magazine will prevent any tendency of the lowermost strips to tilt out of the proper flat, horizontal position; that the presser feet are held in their depressed and operative position to hold 115 the strip in position on the pushers while the strip is carried forward by the pushers and until the pushers reach the end of their forward movement; that the straddle guides will come down at either side of the strip 120 after the latter has been carried forward by the pushers, and will prevent lateral displacement of the strip while the pushers are being withdrawn, act as strippers to hold the strip over the feed bar while the pushers are 125 130

being withdrawn, and also guide the strip to position as it falls to the feed bar after the pushers are withdrawn; that the clamps hold the strip firmly in position on the feed bar 5 until the nipper seizes the strip; that the nipper opens as it approaches the strip and when it reaches the strip closes upon the strip; and that the presser feet, straddle guides and clamps are lifted out of the way 10 in time to permit the feed bar to rotate and the nipper to move forward; that the nipper is moved forward by power driven means which includes a yielding element to permit the forward motion of the nipper to be arrested without discontinuing the application 15 of the power, as the strip is cut off by the cutting tools of the tack or nail machine and again moves forward until it meets the usual stop or gage of the nail cutting machine; that the nipper guiding means (feed bar) derives its motion of rotation, and the nipper its forward motion along the nipper guiding means, from the same common source of power; that said nipper guiding 20 means, intermittently rotated in a single direction, is automatically connected and disconnected from its rotating mechanism at predetermined times, but only when said guiding means is in normal strip-receiving 25 position; and that the stopping and starting of the nipper guiding means, the controlling of the movements of the nipper, and the operation of the mechanisms for delivering the strip to the nipper, are all effected 30 from a single cam shaft, the rotation of which is stopped when the strip has been delivered to and seized by the nipper, and is restarted when the nipper has reached the end of its forward travel; that is, the cam 35 shaft operates only while the nipper is being retracted and a new strip is being brought into place on the feed bar.

I claim:—

1. In a machine of the character described, 45 a rotary feed bar adapted to receive and hold the blank or strip and to afford substantially continuous support therefor, strip-keepers on said feed bar adapted at all times to permit free movement of the strip lengthwise of the feed bar and to hold said strip substantially flat on the feed bar in all positions of the same, and mechanism to open and close said strip-keepers.
2. In a machine of the character described, 55 a feed bar adapted to receive and hold the blank or strip and to afford substantially continuous support therefor, strip-keepers on said feed bar to hold said strip substantially flat on the feed bar, and mechanism to open and close said strip-keepers, said feed bar being provided with a longitudinal guideway, nippers mounted to slide in said guideway, and mechanism to actuate said nippers.
3. In a machine of the character described, 65

a feed bar adapted to receive and hold the blank or strip and to afford substantially continuous support therefor, strip-keepers on said feed bar to hold said strip substantially flat on the feed bar, and mechanism to 70 open and close said strip-keepers, said feed bar being provided with a longitudinal guideway, nippers comprising a pair of jaws, one of which is slidably mounted on and supported by said guideway and the other of which is pivoted to the sliding jaw, and mechanism to actuate said nippers.

4. In a machine of the character described, a feed bar adapted to receive and hold the blank or strip and to afford substantially continuous support therefor, a series of strip-keepers each consisting of an arm pivoted to the feed bar and adapted to swing over the strip, and mechanism to operate said arms in unison. 80

5. In a machine of the character described, a feed bar adapted to receive and hold the blank or strip and to afford substantially continuous support therefor, a series of strip-keepers each consisting of an arm pivoted to the feed bar and adapted to swing over the strip, and a shifting bar mounted to move endwise on said feed bar adapted to operate said arms in unison. 90

6. In a machine of the character described, a feed bar adapted to receive and hold the blank or strip and to afford substantially continuous support therefor, a series of strip-keepers each consisting of an arm pivoted to the feed bar and adapted to swing over the strip, strip-guiding means supported by the forward end of said feed bar, a shifting bar mounted to move endwise on said feed bar, stub end removers carried by said shifting bar, said shifting bar being adapted both to operate said strip-keepers and to retract said stub end removers from the strip-guiding means. 95

7. In a machine of the character described, a magazine adapted to hold a stack 110 of blanks or strips, a feed bar, a nipper mounted to move lengthwise of said feed bar, a pusher adapted to push the lowermost strip from the bottom of the stack out of the magazine and over the feed bar, 115 and movable clamps coöperating with the feed bar to clamp the strip in position flat on the feed bar until it is seized by the nipper.

8. In a machine of the character described, a magazine adapted to hold a stack 120 of blanks or strips, a feed bar, a reciprocating pusher adapted to carry the lowermost strip from the bottom of the stack out of the magazine and over the feed bar, laterally rigid and vertically movable means to hold the strip in position on the pusher until the pusher reaches the end of its forward movement, a nipper mounted to move endwise on said feed bar, and movable clamps 125 130

coöperating with the feed bar to clamp the strip in position flat on the feed bar until it is seized by the nipper.

9. In a machine of the character described, a magazine to hold a stack of blanks or strips, a feed bar, a nipper mounted to move lengthwise of said feed bar, a pusher adapted to push the lowermost strip from the bottom of the stack out of the magazine and over the feed bar, a laterally rigid and vertically movable presser foot adapted when in operative position to hold a strip in position on the pusher until the pusher reaches the end of the forward movement, and means to move said presser foot downward into operative position and upward into inoperative position.

10. In a machine of the character described, a magazine to hold a stack of blanks or strips, a feed bar, a nipper mounted to move lengthwise of said feed bar, a pusher adapted to push the lowermost strip from the bottom of the stack out of the magazine and over the feed bar, a straddle guide to prevent lateral displacement of the strip while the pusher is being withdrawn and to guide the strip to position as it falls to the feed bar, a movable presser foot, and means to hold said presser foot in operative position while the pusher is moving forward and until the straddle guide descends.

11. In a machine of the character described, a magazine to hold a stack of blanks or strips, a feed bar, a nipper mounted to move lengthwise of said feed bar, a pusher adapted to push the lowermost strip from the bottom of the stack out of the magazine and over the feed bar, a straddle guide to prevent lateral displacement of the strip while the pusher is being withdrawn and to guide the strip to position as it falls to the feed bar, and a presser foot adapted to hold the strip in position upon the pusher until the straddle guide descends.

45 12. In a machine of the character described, a magazine adapted to hold a stack of blanks or strips, a feed bar, a reciprocating pusher adapted to carry the lowermost strip from the bottom of the stack out of the magazine and over the feed bar, means to hold the strip in position on the pusher until the pusher reaches the end of its forward movement, means to prevent lateral displacement of the strip while the pusher is being withdrawn and to guide the strip to position as it falls to the feed bar, means to clamp the strip in position on the feed bar after the pusher has withdrawn and a nipper on the feed bar to seize the strip after the pusher has withdrawn and while the strip is clamped to the feed bar.

60 13. In a machine of the character described, a magazine adapted to hold a stack of blanks or strips, a feed bar, a reciprocating pusher adapted to carry the lowermost

strip from the bottom of the stack out of the magazine and over the feed bar, a movable presser foot adapted in its depressed and operative position to keep the strip in position on the pusher until the pusher reaches the end of its forward movement, and straddle guides to prevent lateral displacement of the strip while the pusher is being withdrawn and to guide the strip to position as it falls to the feed bar, clamping means to hold the strip in position on the feed bar after the pusher has withdrawn, a nipper on the feed bar to seize the strip while thus held, and means to withdraw the presser foot, guides and clamping means.

70 14. In a machine of the character described, nipper guiding means, a nipper mounted to travel lengthwise of said guiding means, and mechanism adapted to move said nipper forward including a driving element, a driven element, and a yielding element adapted to permit the forward motion of the nipper to be arrested without discontinuing the movement of the driving element.

75 15. In a machine of the character described, nipper guiding means, a nipper mounted to travel lengthwise of said guiding means, mechanism to impart an intermittent rotary movement to said guiding means, mechanism to drive said nipper forward on said guiding means, and a source of power common to both of said mechanisms, from which source said guiding means derives its motion of rotation and said nipper its forward motion.

80 16. In a machine of the character described, nipper guiding means, a nipper mounted to travel lengthwise of said guiding means, mechanism to impart an intermittent rotary movement to said guiding means, mechanism to drive said nipper forward on said guiding means, and a source of power common to both of said mechanisms, from which source said guiding means derives its motion of rotation and said nipper its forward motion, said nipper driving mechanism including a yielding element adapted to permit the forward motion of the nipper to be arrested without discontinuing the application of the power.

85 17. In a machine of the character described, rotary nipper guiding means, intermittently operated mechanism to rotate said guiding means in a single direction, a nipper mounted to travel lengthwise of said guiding means, mechanism to deliver a blank or strip into position to be seized by the nipper, and mechanism actuated automatically to connect the nipper guiding means and the rotating means when a blank or strip has been seized by the nipper and to disconnect the same when the nipper reaches the forward end of its travel.

18. In a machine of the character described, rotary nipper guiding means, intermittently operated mechanism to rotate said guiding means in a single direction, a coupling member carried by said guiding means for connecting and disconnecting said guiding means and intermittently operated rotating means, and mechanism operated automatically at predetermined times to move 5 said coupling member into operative or inoperative position.
19. In a machine of the character described, nipper guiding means, a nipper movable lengthwise of said guiding means, mechanism to actuate said nipper forward and backward, and mechanism to open the nipper jaws and release the stub end of the strip while the nipper is in its forwardmost position.
20. In a machine of the character described, nipper guiding means, a nipper movable lengthwise of said guiding means, a strip guide supported by the forward end of said nipper guiding means, mechanism 10 to actuate said nipper forward and backward, mechanism to open the nipper jaws and release the stub end of the strip while the nipper is in its forwardmost position, stub end removers at the forward end of said 15 guiding means to engage and hold said stub end while the nipper jaws are retracted therefrom, and mechanism to withdraw said removers and the stub end held thereby from said strip guide.
21. In a machine of the character described, nipper guiding means, a nipper movable lengthwise of said guiding means, a strip guide supported by the forward end of said nipper guiding means, mechanism to 20 actuate said nipper forward and backward, mechanism to open the nipper jaws and release the stub end of the strip while the nipper is in its forwardmost position, stub end removers at the forward end of said 25 guiding means to engage and hold said stub end while the nipper jaws are retracted therefrom, mechanism to withdraw said removers and the stub end held thereby from said strip guide, and means to open said 30 stub end removers when so withdrawn to drop out said stub end.
22. In a machine of the character described, nipper guiding means, mechanism to impart to said guiding means an intermittent motion of rotation, a nipper movable forward and backward on said guid-
- ing means, mechanism to deliver a strip to said nipper, means actuated by the rotation of the guiding means to stop the rotation of the guiding means in correct position to receive the new strip, and mechanism to start the rotation of the guiding means when the strip has been delivered to and seized by the nipper.
23. In a machine of the character described, nipper guiding means, mechanism to impart an intermittent motion of rotation to said guiding means, a nipper mounted to travel lengthwise of said guiding means, and driving mechanism operable by 60 the rotation of said guiding means to drive said nipper forward on the guiding means.
24. In a machine of the character described, nipper guiding means, mechanism to impart an intermittent motion of rotation to said guiding means, a nipper mounted to travel lengthwise of said guiding means, and driving mechanism operable by the rotation of said guiding means to drive said 65 nipper forward on the guiding means, said driving mechanism including a yielding element adapted to permit the forward motion of the nipper to be arrested without discontinuing the rotation of the guiding means.
25. In a machine of the character described, nipper guiding means, mechanism to impart to said guiding means an intermittent motion of rotation, a nipper movable forward and backward on the guiding 70 means, mechanism actuated by said intermittent rotation of the guiding means to control the movement of the nipper, and mechanism controlled by the intermittent rotation of the guiding means adapted to 75 deliver a strip to said nipper.
26. In a machine of the character described, nipper guiding means, mechanism to impart to said guiding means an intermittent motion of rotation, a nipper movable 80 forward and backward on said guiding means, mechanism actuated by the intermittently rotated guiding means to open the nipper jaw when the nipper reaches the end of its forward movement, and again when 85 the nipper engages a fresh strip.

Signed by me at Boston, Massachusetts,
